BOTTLE CAP

August E. Esposito, Brooklyn, N. Y.

Application August 24, 1937, Serial No. 160,709

2 Claims. (Cl. 215—7)

This invention relates to a structurally new and novel screw-cap such as is susceptible of adequate and efficient use in connection with jars, bottles, and similar containers equipped with screw-threaded or similarly constructed filling and pouring necks, the preferred embodiment of the invention having to do with a type of cap which is especially, but not necessarily, adapted for use in connection with tamper-proof containers such as are used for bottling individual brands of liquors.

As will be hereinafter readily discernible, the specific type of cap under consideration is a simple screw-cap of sheet metal, or equivalent material, including a so-called frangible tamper-proof seal or retention band contained in its rim portion.

In reducing to practice the preferred embodiment of the invention, I have found it expedient and practicable to provide an ingenious combination bottle neck and associated screw-cap wherein coacting pawl and rack or equivalent means is adopted to securely fasten the cap in place and to prevent retrograde rotation thereof without breaking the seal legitimately applied at the source of bottling.

Other features and advantages will become more readily apparent from the following description and drawing.

In the drawing, wherein like numerals are employed to designate like features or parts throughout the views:

Figure 1 is an elevational view showing a fragmentary portion of a bottle and disclosing the improved safety-type, tamper-proof cap as perfected in accordance with the principles of the present invention.

Figure 2 is a view like Figure 1 with the cap removed to expose the particular formation or construction of the threaded or equivalent bottle neck.

Figure 3 is a top plan view of Figure 2.

Figure 4 is a section, on an enlarged scale, through the multiple detent-equipped band or annulus forming the safety tamper-proof rim as an integral part of the screw-cap.

Figure 5 is an enlarged fragmentary horizontal section on the line 5—5 of Figure 1.

Figure 6 is an exaggerated fragmentary detail, in section, taken horizontally through the frangible portion of the retention band or collar.

Referring now to the drawing by distinguishing reference numerals, it will be observed that the bottle, container, or equivalent receptacle, is denoted by the numeral 7. As before indicated,

this has a screw-threaded similar neck 8 and in the present instance is improved by the incorporation therein of what may be conveniently called an annular toothed rack 9. This is in effect an endless integral bead formed adjacent the body of the bottle, the same being serrated to provide a plurality of properly pointed and angled retention teeth.

The screw-cap is indicated as a unit by the numeral 10 and is constructed of light weight sheet metal such as tin, aluminum, or the like. It has the customary knurled finger-grip 11 and screw-threaded rim 12 to engage the threads on the neck in the usual way. Formed integral with the screw-threaded skirt or rim of the cap is an outstanding circumferentially slotted annular shoulder forming a fragile jointing web 13 to which the safety tamper-proof retention band 14 is integrally joined. This band 14 surrounds the toothed rack 9 and the shoulder 13 comes into resting contact with the rack teeth.

As shown at the point 15 in Figure 6, this band 14 is preferably formed with an appropriate frangible portion. Any suitable type of a joint may be employed here, such as a type wherein the outer tongue or extension 16 is exposed to permit it to be engaged with a suitable instrument (not shown) to pry the features apart and to easily break the joint and allow the cap to be unscrewed. In addition, the band is provided at 30 equi-distant circumferentially spaced points with struck-in, laterally bent tongues 17 which constitute pawls or detents, these being engageable with the rack teeth 9. It follows that when the screw-cap is applied a "turned home", the detents ratchet over the rack teeth until the cap is fully set. Obviously, the detents, through this pawl and ratchet action, do not interfere with the application of the cap. On the other hand, should the cap be turned in a retrograde direction, it is obvious that this is prevented by the coaction between the detents 17 and the teeth 9. Any severe hand turning to overcome this locking action of the detents will obviously split or rupture either the slotted web 13 or the frangible joint 15, or both, so that tampering can be readily detected.

In practice a cap of this type can be properly photolithographed or otherwise formed for advertising purposes. Moreover, it does not interfere with the application of the customary Federal and State seals. It is evident, however, that these seals as well as the joint 15 would be broken by any unauthorized attempt to remove the cap.

The cap is characterized by requisite simplicity 55

and efficiency, and is susceptible of initial installation by machine or hand. Hence, it is in keeping with present day demands for a tamper-proof closure.

5 The gist of the invention, it will be observed, is in the construction of a cap for bottles or equivalent receptacles having pouring necks. It is immaterial whether the neck be threaded or simply provided with lugs, since the cap is designed to accommodate both types of neck construction. Briefly, then, I have in mind the provision of a cap which is designed to hood over the neck, the cap being either plain or threaded or otherwise constructed for rotary connection with the neck. Said cap is provided with a radially offset retention band 14. It may be connected by a solid web as at 13, or a web having a slot therein, as indicated in Figure 4. Moreover, it is essential, fundamentally speaking, to provide the annular retention band with at least one detent equivalent to one of the features shown at 17, said detent to coact with integral retention elements 9 on the neck of the bottle. There may be a plurality of the elements, as seen by the serrated construction in Figure 2, or there may be simply a few of said lugs distributed circumferentially around the neck of the bottle.

For purposes of interpretation of the claims it is to be pointed out that the disruptible jointing means 16 illustrated in Figure 6 is not considered to be absolutely essential. That is to say, any suitable type of a frangible joint may be fashioned here instead of employing overlapping tongues, as is obvious. The outer tongue or extension 16 in Figure 6 is intended for the harder type metals such as brass and tin plate. In the case of aluminum, however, the metal itself is soft enough to break without the assistance of this tongue construction, and the claims are to be construed accordingly.

40 It is thought that the description taken in connection with the drawing will enable a clear

understanding of the invention to be had. Therefore, a more lengthy description is thought unnecessary.

While the preferred embodiment of the invention is shown and described, it is to be understood that minor changes coming within the field of invention claimed may be resorted to if desired. 5

I claim:

1. In a structure of the class described, in combination, a bottle including a neck having an endless annular serrated radially outstanding bead adjacent the body portion of the bottle said bead being rounded at its peripheral edge, the top of said bead constituting a shoulder and its rounded peripheral edge constituting a toothed 10 rack, a cap fitted on said neck and including a straight portion embracing the neck, said straight portion having at its inner end a radially outstanding endless annular web, said web being apertured to render it frangible and resting in 15 abutting contact on the shoulder portion of said bead, and an integral depending annular collar carried by the outer peripheral edge of said web and extending at right angles to the web, said collar completely surrounding the rack and being 20 provided with an inbent resilient tongue constituting a detent, said detent having ratcheting 25 engagement with the teeth in said rack.

2. As a new article of manufacture, a metal 30 bottle cap including a straight portion having at its bottom a radially outstanding endless annular web, said web being disposed at right angles to said straight portion and provided with a plurality of circumferentially spaced elongated slots to render it frangible, the outer peripheral edge of 35 said web being provided with a depending endless annular retention collar depending at right angles to said web, said collar being of frangible material and having at least one inbent retaining resilient detent.

AUGUST E. ESPOSITO. 40
